Specification for Design.

Patented Nov. 4, 1919.

Application filed March 20, 1918. Serial No. 223,666. Term of patent 3½ years.

To all whom it may concern:

Be it known that I, GUSTAF JOHNSON, a citizen of the United States, residing at Chicago, in the county of Cook and State of Illinois, have invented a new, original, and ornamental Design for Headlight-Lenses, of which the following is a specification, reference being had to the accompanying drawing, in which—

Figure 1 is an elevation of the design; and

Copies of this patent may be obtained for five cents each, by addressing the "Commissioner of Patents, Washington, D. C."

Fig. 2 is a cross-section thereof, on the line 2—2 of Fig. 1.

I claim:—

The ornamental design for a headlight lens as shown.

In testimony whereof I affix my signature.

GUSTAF JOHNSON.
